PLANTER

Milton August Hogan, P.O. Box 17, Ann Arbor, Mich.

Filed Mar. 30, 1959, Ser. No. 55,245

Term of patent 7 years

(Cl. D35—3)

Fig. 1 is a perspective view of a planter showing my new design.

Fig. 2 is a top plan view thereof, the broken-line representation of a flowerpot being omitted for convenience of illustration.

The dominant features of my design reside in the full line portions of the drawing.

I claim:

The ornamental design for a planter, substantially as shown and described.
